UNITED STATES PATENT OFFICE.

WILLIAM H. AINSWORTH, OF WILMINGTON, DELAWARE.

CASING FOR PIPES.

SPECIFICATION forming part of Letters Patent No. 340,073, dated April 20, 1886.

Application filed November 5, 1885. Serial No. 181,954. (No model.)

To all whom it may concern:

Be it known that I, WILLIAM H. AINSWORTH, a citizen of the United States, residing at Wilmington, in the county of New Castle and State of Delaware, have invented certain new and useful Improvements in Pipe-Casings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The object of this invention is to provide an improved protecting-casing for water and other pipes which shall be easily put together, and which shall be simple and cheap in construction.

20 In the drawings, Figure 1 is a side view of the casing. Fig. 2 is a cross-section thereof in a plane indicated by the line 2 2 in Fig. 1. Fig. 3 is a similar section showing the casing packed. Fig. 4 is an enlarged section showing the locking device more clearly, and Fig. 5 is a detail view of one of the temporary retaining-springs.

Like letters designate corresponding parts in all of the figures.

30 The casing is made up of cylindrical sections A A of sheet metal. Each of these sections is made up of two half-cylinders, B B, which are placed around the pipe, C, to be inclosed, with their edges meeting. Adjacent sections A A overlap each other, as in the case of ordinary stove-pipe sections, beads or flanges a a on them holding them in position. Each half-section B has bent edges b b, which are either turned inward, as shown at the left 35 in Fig. 4, or outward, as shown at the right in the same figure. The adjacent edges of the halves of each section are bent in the same manner, and when the several sections A A are put together they are so placed that their bent edges form continuous lines.

40 In order to lock the two halves of each section together, and at the same time fasten adjacent sections together, locking-keys D are provided. These keys consist of strips of 45 sheet metal, the two edges c c of which are bent over toward each other, leaving a slot, d, between them. These keys are slipped end-

wise over adjoining bent edges b b of the half-sections B B, the bent edges c c of the keys passing between the edges b b and the bodies 55 of the half-sections, and the portions e e, connecting the bent portions b b to the bodies of the half-sections, passing through the slot d. Where the joints occur between adjacent sections the keys are slipped by the joint, thus 60 locking the two parts of each of the adjacent sections, and at the same time holding the sections together.

When the casing has thus been put around the pipes, the space between them is filled 65 with a suitable non-conducting packing, such as asbestos or mineral wool. To hold the casing in position concentrically around the pipes while the packing is being introduced, sheet-metal springs E E are employed. Each of 70 these springs is formed out of one piece of metal, and has a curved bottom portion, f, which conforms to the curve of the sections A, a radial portion, g, springing from said base portion, a top portion, h, curved to conform to the pipe C, and a second radial portion, i, extending from the top portion down toward the base portion. Normally the spring of the metal holds the radial portion i away 75 from the base portion f. The radial portion 80 i also limits the movement of the side f, and prevents the same from being bent downward by the weight of the casing. The length of the base portion is less than the semi-circumference of the casing. To retain the 85 unfilled end of a section of the casing in position, two of these springs E E are used on opposite sides of the pipe C. They are inserted by depressing the top portions, when they can be readily put in place between the pipe 90 and casing, and upon releasing the top portions they spring up against the pipe and hold the casing centrally around it. When the space has been filled, these springs are removed, another section of the casing is put 95 around the pipe and locked, and the springs are inserted in the open end of that section.

In order to permit access to the joints of the pipe C without removing the casing, they are left exposed, and the casing is reduced at 100 these points by a reduced section, F. This section is conical in shape, being at its smaller end of the diameter of the pipe C, and expanding at its larger end to the dimensions of the

rest of the casing. This reduced section is composed of two parts, B B, which are locked together in the same manner as those of the cylindrical sections.

- 5 In filling the space between the casing and inclosed pipe with asbestos, mineral wool, or other light non-conducting material, it is sometimes found dangerous to have the light non-conducting material brought in direct contact with the pipe. To guard against this danger the pipe is first wrapped with one or more layers, G, of asbestos paper, or other close non-conducting inflammable wrapping, and then the remaining space between the pipe thus wrapped and the outer casing is filled with the light filling material H.
- 10
- 15

I claim as my invention—

1. A pipe-casing composed of cylindrical sections A A, placed end to end, each section being composed of two similar semi-cylindrical portions, B B, which are put around the pipe to be inclosed, with their longitudinal edges b b in contact, the adjoining longitudinal edges b b of said half-cylinders being bent away from each other in opposite directions, in combination with elongated locking-keys D D, having oppositely-bent edges c c, which take under the adjoining edges b b of the half-cylinders B B, said keys also lapping by the
- 20
- 25

joints between adjoining sections A A, with 30 their bent edges taking under the bent edges b b of said adjoining sections A A, whereby said sections A A and the half cylinders B B of each section are locked together, substantially as set forth.

35

2. The casing and the inclosed pipe, in combination with temporary unattached holding-springs, said springs having concentric portions which rest against the surfaces of said casing and pipe, respectively, substantially as 40 set forth.

3. The casing A and the inclosed pipe C, in combination with temporary unattached holding-springs E E, each of said springs having a curved side, f, which fits against the inner 45 surface of the casing A, a curved side, h, which fits against the outer surface of the pipe C, a radial portion, g, connecting the sides f h, and a radial portion, i, connected to side h, which limits the play of side f, substantially as set 50 forth.

In testimony whereof I affix my signature in presence of two witnesses.

WILLIAM H. AINSWORTH.
